C. T. WESTMORELAND.
LOCKING DEVICE FOR DESKS AND THE LIKE.
APPLICATION FILED JAN. 3, 1913.

1,139,939.

Patented May 18, 1915.

UNITED STATES PATENT OFFICE.

CRAWFORD THEODORE WESTMORELAND, OF HIGH POINT, NORTH CAROLINA, ASSIGNOR
TO MYRTLE DESK COMPANY, A CORPORATION OF NORTH CAROLINA.

LOCKING DEVICE FOR DESKS AND THE LIKE.

1,139,939.

Specification of Letters Patent. Patented May 18, 1915.

Application filed January 3, 1913. Serial No. 740,081.

To all whom it may concern:

Be it known that I, CRAWFORD THEODORE WESTMORELAND, a citizen of the United States, residing at High Point, in the county 5 of Guilford and State of North Carolina, have invented certain new and useful Improvements in Locking Devices for Desks and the like, of which the following is a specification.

10 This invention relates to improvements in locking devices for desks, cabinets or other pieces of furniture having a plurality of drawers the locking of which is controlled by some movable portion usually under control of lock and key and common to all the drawers. For example, in the case of roll top desks it is common to control the locking of the tiers of drawers by the roll top, and in the case of a flat top desk to control 15 the locking of a plurality of the drawers from one drawer, which later is locked and unlocked by a key. It is a common fault with devices of this character now generally in use that the locking mechanism for the several 20 drawers easily gets out of order, due in some cases to the more or less complex mechanism employed, and in others to faulty construction which will not stand the rough usage to which such mechanism is ordinarily subjected. The ideal mechanism for this 25 purpose should be of such a nature as to stand rough or severe operation without getting out of order. For example, all such locking devices as are operated by the roll top of desks must be capable of withstanding considerable rough treatment as it were, without getting out of order, owing to the common practice of sending back the roll tops of such desks with considerable force 30 in opening them. The same thing applies perhaps to a lesser degree to desks of the flat top variety in which the closure of one drawer automatically locks a series of other closed drawers, but in the latter case the controlling drawer is not usually closed with the violence that is common in opening a 35 desk of the roll top type.

The object of this invention is to provide a locking device of the above character 40 which shall possess the desirable qualities stated, and which shall at the same time be extremely simple in construction and sure in operation.

In order to more fully describe my said

invention, reference will be had to the accompanying drawings wherein:—

Figure 1, represents in vertical section a desk of the roll top type equipped with one form of my said invention; Fig. 2, a top plan view of the said locking mechanism, 50 showing parts of the desk broken away, and Fig. 3, a fragmentary section on line 3^x—3^x Fig. 1, looking down.

In the accompanying drawings, 1 represents a desk of what is known as the roll top type having a tier of drawers 2, 3 and 4, and a flexible or roll top 5 adapted to travel in grooves 6, at each end of the desk. The construction of such tops is well known, and since no novelty is herein claimed for 65 this portion of the desk, further description of the construction of this portion is not necessary here. Such roll tops are, as is also well known, usually under control of a lock and key, and when unlocked 70 and slid back usually operate mechanism which unlocks the tier drawers, such as drawers 2, 3 and 4.

The locking mechanism which I provide in the present case, comprises preferably a 75 wooden upright 7, made fast top and bottom, respectively, to two brackets 7^a and 7^b which are in turn made fast preferably by screws to the back of the desk as shown, the said upright being in the rear of the tier 80 of drawers 2, 3 and 4; a series of preferably metal locking dogs 8, 9, and 10, pivoted to one face of said upright; a movable member 11, preferably a wooden rod or bar, to one face of which the tails of all the said 85 dogs are pivotally secured, and a spring 12 attached in the case shown at one end to the stationary upright 7, and at the other end to the movable member 11.

The heads of the several dogs are provided, respectively, with shoulders 13, 14 and 15, adapted to engage the inner side of the rear of the drawers.

The upper end of the member 11 is provided with an extension or head 16 which 100 passes upward through an opening 17 in the flat top of the desk. This head is in alinement with the travel of the roll top 5, and is adapted to be struck directly by the rear of said roll top when the latter is slid 105 back in the open position. When the roll top thus strikes the head 16, the member 11 is sent downward against the tension of

the spring 12, extending the same and sending the shoulders of the several dogs 13, 14 and 15 clear of the upper rear edges of said drawers, thus unlocking them. When the 5 pressure of the roll top is released from the head 16, as, for example, when the roll top is slid forward to close the desk, the member 11 will rise under the action of the spring 12 and will send all the dogs into 10 the locking position, as shown in Fig. 1. The upward movement of the member 11, and therefore the downward movement of the heads of the several dogs is limited by stops 18, 19 and 20, which the dogs are 15 adapted to engage.

If all the drawers are closed at the time the dogs are sent into the locking position, they will all be locked as shown. If, however, one or more of the drawers is not 20 in the closed position when the pressure on the head 16 is released, any of the drawers may be locked by pushing them in to the full closed position. When this is done the rear end of the drawer engages its dog, the 25 head of which yields upwardly against the action of spring 12 and permits the rear end of the drawer to pass the shoulder of the dog, after which the dog drops to the locking position with its shoulder on the 30 inside of the rear of the drawer.

For the purpose of causing the rear end of the drawers on engagement with the heads of the dogs to raise them as described, the heads of the said dogs are provided, 35 respectively, with curved cam faces 21, 22 and 23.

The mechanism herein shown and described is, as will be readily seen, extremely simple, and is particularly well adapted to 40 stand the rough usage to which such parts are usually subjected, as pointed out in the general introduction to this specification.

Another important advantage of my improved locking device is that the entire 45 mechanism, including the attachment of the upright 7 to the brackets 7^a and 7^b and the attachment of the member 11 to the locking dogs which solely support and carry the same, may be assembled before it is put in 50 the desk. Again the connection of the spring 12 from one of the upright members to the other, as shown, is a decided improvement over the ordinary way of arranging the springs of this class of locking de-

vices. Also, the form of locking dog herein 55 shown may be and preferably is stamped out of plate or sheet metal which greatly reduces the cost of manufacture. These dogs possess the further advantage that they will not split or break in operation as is 60 the case with the wooden locking members commonly in use.

It should be understood, however, that while I have herein shown my invention as applied to desks only, it may equally as well 65 be applied to cabinets, or other pieces of furniture having a series of drawers, the locking of which is controlled from some one movable part of the article ordinarily under lock and key, and in the claims I use 70 the word "desk" in a generic sense to cover all such articles.

It will be further understood that modifications may be made in the construction of the locking mechanism itself without departing from the true spirit of my invention. 75

What I claim is:

A desk having a plurality of drawers and a roll top, in combination with an upright 80 bar rigidly secured to the desk in the rear of said drawers, a plurality of locking dogs fulcrumed intermediate their ends upon said bars, each dog being provided with a locking head adapted to engage with the rear 85 end of an individual drawer, an upright bar pivotally connected to the tails of all said dogs and extending upward through an opening in said desk in position to be struck directly upon its top by the roll top 90 of said desk, a spring connected to both said bars and forming a yielding connection between them against the resistance of which any of the dogs in the locking position may yield to receive and lock an individual 95 drawer, means on the first mentioned bar to limit the movement of said dogs by said spring, said bars, dogs, spring and limiting means adapted to be assembled completely 100 outside of the desk and inserted into an operative position therein thus assembled.

In testimony whereof I affix my signature in presence of two witnesses.

CRAWFORD THEODORE WESTMORELAND.
